CLAIM

The ornamental design for an industrial personal digital assistant, as shown and described.

DESCRIPTION

FIG. 1 is a perspective view of an industrial personal digital assistant showing our new design;
 FIG. 2 is another perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof; and,
 FIG. 8 is a bottom plan view thereof.
